UNITED STATES PATENT OFFICE

2,134,804

AIR HEATER FOR BLAST FURNACES

Alfred Schack, Meerbusch, near Dusseldorf, Germany, assignor to Rekuperator G. m. b. H., Dusseldorf, Germany

Application January 25, 1937, Serial No. 122,329
In Germany January 28, 1936

3 Claims. (Cl. 263—20)

Many proposals have been made for the construction of known types of air heaters for blast furnaces operating on the regenerative principle such as recuperative air heaters in which the 5 conduits are provided as steel tubes. None of these proposals have however been practically successful.

Heat resisting steels have at high temperatures an exceedingly low permanent tensile 10 strength representing only a fraction of the tensile strength determined in the laboratory at those temperatures by the usual rapid breakdown test for tensile strength, and thus heat resisting steels are not in general adapted for use 15 at the maximum temperatures of the hot gas inlet commonly used in air heaters for blast furnaces.

The present invention has among its objects to provide steel tubes in air heaters of blast furnaces, of such form and composition as to be durable and adapted for effective use at the high 20 temperatures usually applied in such air heaters.

According to the invention air heaters for blast furnaces using steel tubes have the tubes 25 so formed or constructed and disposed that in all situations in which in use of the air heater the temperature of the metal of the tubes exceeds approximately 900° C., (at which temperature the tensile strength is very greatly reduced) 30 the internal diameter of the heating tubes is provided of 40 mm. or under that dimension. Usually an internal diameter of less than 40 mm. is used.

The tube diameter used in known types of 35 heat exchangers hitherto employed for other purposes in which such large volumes of air are used as in the air heaters of blast furnaces has always been much greater. Having regard to the cost of production, even in the case of ordinary air heaters steel tubes of at least 50 mm. 40 diameter and usually between 50 and 100 mm. diameter and even larger tubes are employed where large quantities of air are required.

It will be understood that the reason for employing a small diameter of tube according to the invention is that blast furnaces operate with air pressures of about one atmosphere super-pressure and at a high temperature. If therefore a tube of large diameter be exposed internally to such a pressure and the temperature applied exceed 900° C. the tube wall will expand as the result of the high stress thus imposed and in a few months of use will fracture. The effective life of such tubes at high temperatures 55 such as indicated is thus unduly short, a practical advantage of some importance that outweighs the disadvantage of using a very large number of small diameter tubes and the cost of their manufacture, for the necessary considerable through-put of air required in such heat-

ers. The applicant has found that if the tube diameter be maintained very small the internal stress set up under such a high temperature as that commonly used in the hot gas inlet of air heaters for blast furnaces may be so low that 5 the tubes will last for many years. In some cases however the temperature and pressure of the air required by blast furnaces are so high that the mere reduction in diameter of the tubes made merely of heat-resisting chromium steels 10 is insufficient to meet practical requirements, for even a very small diameter of tube when the tube is used under conditions where its temperature is about but does not exceed 1000° C. and the air pressure is not more than one at- 15mosphere would not prevent the permanent expansion of the tube when made of chromium steel.

The invention has among its objects to avoid this disadvantage by the use of heat-resisting 20 steel having a particular high permanent tensile strength under high temperature.

According to the invention therefore the more highly stressed sections or parts of the tubes in a tubular air heater are made of a different steel 25 which however has similar resistance to heat as chromium steel but in addition has a high permanent tensile strength under high temperature. Among such heat-resisting and strong steels are austenitic chromium nickel steels or ferritic 30 steels which are not only alloyed with chromium but also with molybdenum or tungsten.

By reason however of the difficulty of shaping and the more expensive constituents of such alloys, such steels are more expensive than the 35 alloys of similar heat resistance which have not so permanent tensile strength. Therefore next to the heat-resistant steels which have particularly strength under heat a heat-resisting steel with less tensile strength under temperature is 40 employed according to the invention at those positions at which smaller demands are made on the material.

According to the invention moreover the drums or collectors between which the banks of 45 the heating tubes extend are similarly constructed of small dimensions and in addition a number of small drums or collectors are provided.

According to the invention moreover the drums or collectors are not constructed as hitherto of rectangular cross-section and of flat limiting or defining walls but they are given a form that is curved and non-angular for example as a cylinder with curved ends, a sphere or an ellipsoid. 55

According to the invention moreover the drums or collectors must always have a much larger diameter than the tubes leading into them and those drums or collectors, especially those adjacent the hot gas inlet, are according to the in- 60

vention made of the more expensive heat resisting steel that has high permanent tensile strength under heat, whereby greater durability of the drums or collectors near the hot gas inlet is secured.

5 A tubular air heater constructed according to the invention is illustrated in Figures 1 and 2 of the accompanying drawings which are vertical sections mutually at right angles.

10 In both figures *a* is the hottest section or length of the tubes which must be made of a heat-resisting steel having a high permanent tensile strength under high temperature such as an austenitic heat-resisting steel and with an internal 15 diameter of less than 40 mm. *b* is the next section or length of the tubes which is constructed of heat-resisting steel not having high permanent tensile strength under high temperature, for example ferritic chromium steel, and of the same 20 diameter as those of the first section, and the next section or sections of the tubes *c* is or are advantageously constructed of ordinary ingot steel. *d* and *i* are the drums or collectors into which the respective ends of the tubes *a*, *b*, *c* may be welded. The walls of the drums or collectors *d* are curved and the drums or collectors *d* are formed of heat-resisting steel having a high permanent tensile strength under high temperature such as austenitic chromium nickel steel. The hot gases are admitted at *e* and leave at *f* while the cold air enters at *g* into the upper drums or collectors *i* and the hot air leaves the lower drums or collectors *d* at *h*. The upper drums or collectors *i* are built to form a right angle and may be made of ordinary steel as the temperature of the heating gases at this position is so low that the permanent tensile strength of ordinary steel renders it possible to employ that material.

40 The lengths or sections *a*, *b*, *c* may be more than 3 and the lengths of sections of the respective tubes may be connected together by welding.

Examples for the composition of the steels

45 (1) Austenitic chromium-nickel-steel for the collectors *d* (high permanent tensile strength):

	Per cent
Ni	22
Cr	22
Fe	56

(2) Austenitic chromium-nickel-steel for the tubes *a* (high permanent tensile strength):

	Per cent
Ni	22
Cr	22
Fe	56

(3) Ferritic chromium-steel for the tubes *b* (low permanent tensile strength):

Cr	20
Fe	80

I claim:

1. A tubular air heater for blast furnaces in which steel tubes are used whose heated ends are exposed to high temperatures, wherein for the purpose of protecting such tubes against distortion and creeping in service the air-capacity of the air heater is made up of a large number of tubes which are provided of a heat-resisting steel and with an internal diameter that is only about 20 40 mms. or under.

2. A tubular air heater for blast furnaces, in which the air-heating surface is formed by steel tubes, the most highly heated parts of which are exposed to temperatures of 900° C. and over, having tubes the internal diameter of which is only 25 40 mm. or under, the parts of the tubes that are most highly heated consisting of a mechanically heat-resisting steel that will withstand the formation of scale, such as austenitic chromium 30 nickel steel, and the directly adjacent parts consisting of a mechanically non-heat-resisting steel on which scale will not form, such as ferritic chromium steel.

3. A tubular air heater for blast furnaces, in which the air-heating surface is formed of steel tubes the most highly heated parts of which are exposed to temperatures of 900° C. and over, the said tubes being connected at the two ends into hollow headers, the tubes, for the purpose of their protection against distortion and creeping in service, being of an internal diameter of about 40 mm. or under and being of a heat-resisting steel and the hollow headers being constructed of a heat-resisting steel having a high permanent tensile strength at high temperature such as austenitic chromium nickel steel and in a form presenting curved and non-angular surfaces and of small dimensions, the number of headers being a multiple for the complete assembly of tubes.

ALFRED SCHACK. 50
